UNITED STATES PATENT OFFICE.

CHARLES H. BESLY, OF CHICAGO, ILLINOIS.

PAPER-HOLDING DEVICE FOR FILES.

SPECIFICATION forming part of Letters Patent No. 423,589, dated March 18, 1890.

Application filed December 18, 1888. Serial No. 294,012. (No model.)

To all whom it may concern:

Be it known that I, CHARLES H. BESLY, of Chicago, in the county of Cook and State of Illinois, have invented certain new and useful Improvements in Paper-Holding Devices for Files; and I do hereby declare that the following is a full, clear, and exact description thereof, reference being had to the accompanying drawings, and to the letters of reference marked thereon, which form a part of this specification.

This invention relates to the paper-holding devices of files, and is more especially intended for attachment to the backs or bases of files to removably hold the perforated index-sheets of such files, or to hold the sheets themselves when the latter are perforated to receive the rod of the holder.

The invention consists, primarily, in a spring-rod supported by the file and a fastening for the free end of the rod, also secured to the file, whereby the rod is held locked at its top or free end, so as to retain the papers thereon until it is required to remove them, while upon the detachment of the rod from its fastening the rod will spring forward away from the fastening, normally assuming an inclined position with respect to the back or base of the file to which the device is attached, so as to allow the papers or index-sheets to be removed and others substituted in their place without hindrance from the fastening.

The invention consists, less broadly, in a paper-holding device of the spring order, constructed of spring wire or metal bent into the desired form and adapted to be attached to the back or base of a file.

The invention is mainly shown applied to a file of the box form, having therein a series of perforated index-sheets strung on the spring-rod of the holder.

In the accompanying drawings, Figure 1 is a filing-case shown in a section taken transversely to the back of the case, or in line 1 1 of Fig. 2. Fig. 2 is a section parallel to the back of the case, or in line 2 2 of Fig. 1. Figs. 3 and 4 are fragmentary perspectives showing a portion of the back of the filing-case with the improved paper-holding device attached thereto. Fig. 5 is a perspective view of a modification. Fig. 6 is a perspective

showing another modification, in which the paper-holder is connected at the bottom with the file or file-base. Fig. 7 is a top view of the modification shown in Fig. 6. Fig. 8 shows the paper-holder secured in a recess of a file-back by insertion of a widened rear part of the holder in lateral grooves at the back part of the recess. Fig. 9 is a similar view on an enlarged scale with part broken away.

A represents a filing-case, of which A' is the back, and A² the bottom.

B is a series of index-sheets provided with apertures at b, adapting them to be strung on the holding-rod of a file.

C represents the index-holding rod, which, in the form herein illustrated, is constructed of spring-wire and of the same piece with the back portion C' and a bottom part c, which connects the back part C' with the rod C.

The hook or catch is shown at c', and in all figures except Fig. 4 it is part of the single piece which forms the remainder of the device.

The rod C, the bottom c, and the back C' in Figs. 1 to 4, inclusive, are of double wire; but the hook c' is single.

In these figures it will appear that the wire is bent upon itself at the end of the paper-holding rod C, so as to afford an open loop c² at its upper end to receive the hook c'. The two parts of the wire where they form the back portion C' of the holder are brought into contact with each other at the upper and lower portions of this back part, but are centrally separated or bent outwardly in opposite directions, as shown in Figs. 2, 3, and 4, in a plane at right angles to that of the bottom c, so as to afford a wide bearing against the back A' of the filing-case, whereby the holder is retained in its proper position, or with the rod C at a distance in front of the surface to which the holding device is attached. So constructed the holding device is conveniently secured in place against the back of the case by means of staples D D near the upper and lower portions of the back part C', as seen in Figs. 1, 2, 3, and 4, or by means of screws arranged on opposite sides of the back wire, as indicated in Fig. 5, or by inserting the widened back part C' into lateral grooves e e at the rear of the recess E,

as seen in Figs. 8 and 9. In the last two modes of connecting the holder with the case the holder may be removed at pleasure. As giving better support to the holder when attached by insertion in the grooves *e c*, its back part may have the form shown in Figs. 4 and 5. If this back part *C'* be bent out of line—as, for example, bent forward at its middle part before insertion—it will bind in the grooves *e e* and retain its place with all needful firmness till its removal is desired.

In Fig. 4 the hook *c'* is a separate piece of wire thrust into the back of the case *A*, and in Fig. 5 the whole device is made of a single piece of wire, not folded or doubled upon itself, but bent out or offset in its rear portion at both sides of the central plane of the holder to give the desired breadth of bearing against the back of the filing-case.

In Figs. 6 and 7 the paper-holder is shown applied to the bottom or base-board of a file, the lower connecting part *c* of the holder being in this instance given the proper form for a desired breadth of bearing upon the part to which the holder is secured.

When the spring-rod *C* is freed from the hook *c'*, it assumes an inclined position, (shown by dotted lines in Figs. 1 and 3,) with its upper end forward of the hook far enough to admit the papers to be filed. It stands in this position with a degree of rigidity which enables the index or other sheets to be readily applied thereto, and when engaged with the hook it maintains its engagement therewith

firmly by reason of its forward pressure due to the elasticity of the material of which it is made and the normally-inclined position given it when free.

I claim as my invention—

1. The combination, with a file, of a spring paper-holding device made of a single piece of spring-wire and comprising a back part, a hook at the upper end of the back part, a rod to enter the perforations of the sheets, and a bottom part connecting the lower end of the rod with the back part, that part which bears upon and connects with the file being laterally bent to give breadth, substantially as described.

2. The combination, with a file, of a spring paper-holding device consisting of a paper-holding rod, a back part, a connection between the bottoms of the rod and the back part, and a hook at the top of the back part, all made of a single piece of wire formed into a loop at the top of the rod, and extending double to the upper part of the back portion and separated between the ends of the back or bottom parts, substantially as described, and for the purposes set forth.

In testimony that I claim the foregoing as my invention I affix my signature in presence of two witnesses.

CHARLES H. BESLY.
